CLAIM

The ornamental design for a toy building element, as shown and described.

DESCRIPTION

FIG. 1 is a front perspective view of the toy building element;

FIG. 2 is a rear elevational view thereof;

FIG. 3 is a front elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The portions of the design shown in broken lines form no part of the claimed design and are solely for illustrative purposes.
